UNITED STATES PATENT OFFICE.

MICHAEL TROOTNEFF AND JOHN GROMEEKO, OF SAN FRANCISCO, CALIFORNIA.

DISINFECTION APPARATUS.

Application filed June 22, 1925. Serial No. 38,800.

Our invention relates to improvement in disinfecting apparatus wherein a disinfecting agent is sprayed directly upon a heated plate and vaporized to form a vapor 5 adapted to permeate and disinfect large quantities of clothing and other articles in a dry condition without the use of steam.

In disinfecting large quantities of clothing and the like, a common practice heretofore has been to hang the garments or articles to be disinfected in a closed room and to introduce a disinfecting agent by means of steam. Such practice makes it necessary that the garments be hung loosely as otherwise the materials become weighted down 10 with moisture and the free circulation of the disinfectant through the garments is so impaired as to prevent an efficient and complete disinfecting thereof. Furthermore 15 the garments absorb so much moisture that they must be removed and dried before they can be again used or packed away. Such steam process cannot be used at all for disinfecting garments or the like made of fur 20 as the moisture ruins the skins.

Our invention is therefore designed to avoid these objections and to afford a means for efficiently disinfecting materials of all kinds, the primary object of our invention 30 being to provide an improved apparatus which will facilitate the disinfecting of large quantities of clothing in a dry condition.

Another object is to provide a device in 35 which the articles to be disinfected may be packed compactly during the disinfecting process, and which will permit the articles to be used or packed without need for subsequent drying.

40 A further object is to provide an improved apparatus which will facilitate the vaporization of a disinfecting agent and which will facilitate the permeation of the vapor through articles to be disinfected.

45 Another object is to provide an improved apparatus having means for protecting articles from injury during the disinfecting thereof.

A still further object is to provide an 50 apparatus of simple and improved construction which may be economically manufactured and installed and which may be readily transported and installed within any available compartment where required.

55 We accomplish these and other objects by means of the device disclosed in the

drawings forming a part of the present specification wherein like characters of reference are used to designate similar parts throughout said specification and drawings 60 and in which,

Fig. 1 is a transverse section through the apparatus showing the construction and arrangement thereof.

Fig. 2 is a broken plan view of the apparatus. 65

Fig. 3 is a broken front elevation of the apparatus.

Fig. 4 is a broken sectional detail showing the construction and arrangement of the 70 disinfectant vaporizing elements.

Referring to the drawings the numeral 1 is used to designate in general a furnace provided with a fire box 2 and an ash box 3 having doors 4 and 5 respectively. Grate 75 bars 6 are mounted between the fire box and the ash box adjacent the front of the furnace, and a baffle 7 is mounted within the fire box 2 immediately back of the grate bars 6 to deflect heat upwardly against a crown 80 plate 8 mounted across the top of the furnace. The crown plate 8 is provided with corrugations 9 upon its upper surface and ribs 11 upon its under surface for a purpose hereinafter more fully explained. 85

A chimney 12 is connected into the back of the fire box 2, said chimney ascending gradually in zigzag manner immediately in back of the furnace to form a large heating surface, at an elevation nearly the same 90 as the elevation of the crown plate 8.

Racks are mounted above the furnace 1 and the zigzag chimney 12, said racks consisting of a plurality of spaced rack bars 13 supported upon suitable transverse supporting members 14. The rack bars 14 are arranged at a slight distance above the upper surfaces of the furnace and chimney and are arranged to receive and support relatively large quantities of garments or other 100 articles, not shown, to be disinfected. 95

Shields 16 and 17 are mounted between the furnace and chimney and the rack bars 14 to protect the rack bars and articles supported thereon from being overheated or 105 burned by the heat from the furnace or chimney. The shields 16 and 17 are preferably made in separate portions substantially covering the top of the upper surfaces of the furnace and chimney respectively, the shield 16 being supported above the furnace by legs 18 secured upon the 110

sides of the furnace and extending upwardly therefrom to the desired elevation. The shields consist of metallic frames upon which are secured webs of asbestos fabric or 5 other suitable non-inflammable and heat insulating material having a plurality of perforations 19 formed therein to permit the free circulation of air and vapor upwardly therethrough as hereinafter more 10 fully explained. The shield 17 is preferably supported along its forward edge by means of hooks 21 engaging eyes 22 formed in the corners of the frame of the shield 16 and along its rearward edge by means of 15 wires or other suitable members adapted to hold the shield in substantially horizontal position at the desired elevation.

A disinfectant spraying element 23 is mounted immediately above the crown plate 20 8, said element preferably consisting of a pipe extending in horizontal position across the plate 8 and having perforations 24 upon the under side thereof. The pipe is held by 25 clamps 26 mounted upon the upper ends of rods 27 extending upwardly from the top of the furnace. The rearward end of the pipe 23 is closed and the forward end is adapted to be connected to a container 28 from which is supplied a liquid disinfecting agent. The 30 pipe 23 is positioned at a slight elevation above the crown plate 8 and the perforations 24 are so arranged that when the disinfecting agent is dispensed through the pipe it will be projected as a fine spray over substantially the entire upper surface of the 35 crown plate.

In operation the furnace 1 is installed within a closed compartment with the doors 4 and 5 of said furnace accessible through 40 an opening 29 in a wall 31 closing the front of the compartment along the front of the furnace. The zigzag chimney is arranged in back of the furnace and extended out of the compartment in any convenient manner. 45 One or more sets of rack bars 13 are arranged in spaced relation above the shields 16 and 17 in accordance with the size and height of the compartment to receive the articles to be disinfected.

50 The articles to be disinfected are placed in any convenient manner upon the bars 13 and a fire built in the furnace. The fire is disposed directly under the crown plate 8 which is quickly heated to a high degree, the heating 55 of said plate being facilitated by the downwardly disposed ribs 11 which operate to increase the quantity of heat absorbed and conducted into the body of the plate. After the plate 8 has been heated a liquid 60 disinfecting agent is sprayed from the pipe 23 onto the heated upper surface of a plate 8 whereby said agent is vaporized and caused to diffuse throughout the compartment. The corrugations 9 increase the area 65 of heated surface upon which the agent

may be sprayed and facilitate the instantaneous vaporization of the disinfecting agent.

The heat from the furnace and from the heated zigzag chimney causes an upward movement of air from the heated surfaces whereby the vaporized disinfectant is carried upwardly through the perforations 19 in the shields 16 and 17 and caused to permeate all articles placed upon the rack bars 13. The upward movement of the heated air thus operates to carry the vaporized disinfectant directly into the articles and at the same time maintains a relatively high temperature within the compartment whereby condensation is prevented.

The disinfecting agent may be of any desired character adapted to meet the requirements of any particular condition, an aqueous solution of formaldehyde such as is commonly known as formalin being particularly adapted for most ordinary purposes, but other disinfectants may of course be used if desired.

The articles to be disinfected may be stacked in any convenient manner upon the rack bars 13, as the dry air and vapor circulates freely through and around such articles and the vapor permeates such articles even though folded and stacked in piles. After remaining in the disinfecting compartment for the required period of time the articles are removed, and being warm and dry may be immediately placed in use or packed for storage as the occasion may require. This feature is of particular value in connection with the use of the apparatus in disinfecting the clothes of soldiers, our improved apparatus making it possible for soldiers or others to place their clothing in individual sacks in the compartment for disinfecting whereby the clothes of each person may be kept separate from those of other persons and enable each person to readily identify his own clothes when removed from the disinfecting compartment. When removed the clothes may be worn immediately without the necessity of waiting for them to be dried as in the heretofore common practice above referred to.

The several elements of the apparatus above described are readily moved from place to place and may be easily installed in any available compartment, thus avoiding the labor and expense of a permanent installation. While we have illustrated and described what we consider to be the preferred embodiment of the invention, the details of construction and arrangement are of course subject to modification in numerous ways without departing from the spirit of the invention.

Having thus described our invention what we claim as new and desire to secure by Letters Patent is:

1. A disinfecting apparatus comprising

- the combination with a closed compartment of a furnace mounted within the compartment; a crown plate mounted above the furnace and arranged to be heated thereby; 5 means for supporting articles to be disinfected above the furnace; and means for dispensing a disinfecting agent onto the crown plate to be vaporized whereby the vapor may permeate and disinfect the articles.
- 10 2. A disinfecting apparatus comprising the combination with a closed compartment of a furnace mounted within the compartment; a crown plate mounted above the furnace and arranged to be heated thereby; 15 means for supporting articles to be disinfected above the furnace; and means for dispensing a disinfecting agent onto the crown plate to be vaporized whereby the vapor may permeate and disinfect the articles. 20 and a shield mounted between the furnace and the articles to prevent the burning of said articles.
3. A disinfecting apparatus comprising the combination with a closed compartment 25 of a furnace mounted within the compartment; a crown plate mounted above the furnace and arranged to be heated thereby; means for supporting articles to be disinfected above the furnace; and means for dispensing a disinfecting agent onto the crown plate to be vaporized whereby the vapor may permeate and disinfect the articles; and a shield mounted between the furnace and the articles supported thereover to 30 protect said articles from burning and perforated to permit a free circulation of air and vapor thereto.
4. A disinfecting apparatus comprising the combination with a closed compartment 40 of a furnace mounted within the compartment; a crown plate closing the top of the furnace and arranged to be heated thereby; a zigzag chimney connected into the back of the furnace; racks mounted above the 45 furnace and the chimney for supporting articles to be disinfected; shields mounted between the furnace and the racks to protect articles supported thereon from burning; and means for dispensing a disinfecting 50 agent upon the crown plate to be vaporized whereby the vapor may be carried upwardly by heat from the furnace and chimney to permeate and disinfect the articles.
5. A disinfecting apparatus comprising 55 the combination with a closed compartment of a furnace mounted within the compartment; a crown plate closing the top of the furnace and arranged to be heated thereby; a zigzag chimney connected into the back 60 of the furnace; racks mounted above the furnace and chimney for supporting articles to be disinfected; shields mounted between the furnace and the racks to protect articles supported thereon from burning, said shields 65 having perforations formed therein to per-
- mit a free circulation of heated air upwardly therethrough; and means for dispensing a disinfecting agent upon the crown plate to be vaporized whereby the vapor may be carried upwardly by the heated air to permeate and disinfect the articles. 70
6. A disinfecting apparatus comprising the combination with a closed compartment of a furnace mounted within the compartment; a crown plate closing the top of the 75 furnace and arranged to be heated thereby; a chimney connected into the back of the furnace; racks mounted above the furnace and the chimney for supporting articles to be disinfected; a perforated pipe mounted above the furnace for spraying a disinfecting agent upon the crown plate whereby said agent may be vaporized and the vapor caused to permeate and disinfect the articles. 80
7. A disinfecting apparatus comprising the combination with a closed compartment of a furnace mounted within the compartment; a crown plate closing the top of the 85 furnace and arranged to be heated thereby; a chimney connected into the back of the furnace; racks mounted above the furnace and the chimney for supporting articles to be disinfected; a perforated pipe mounted above the furnace for spraying a disinfecting agent upon the crown plate whereby said agent may be vaporized and the vapor caused to permeate and disinfect the articles; and perforated shields mounted between the furnace and chimney and the 90 racks to protect the articles from burning. 95
8. A disinfecting apparatus comprising the combination with a closed compartment of a furnace mounted within the compartment; a crown plate closing the top of the 100 furnace and arranged to be heated thereby, said plate being provided with corrugations upon its upper surface; a perforated pipe mounted above the crown plate for spraying a disinfecting agent upon the corrugated surface thereof whereby said agent may be vaporized; and racks mounted above the furnace to support articles to be disinfected by the vaporized agent. 105
9. A disinfecting apparatus comprising the combination with a closed compartment of a furnace mounted within the compartment; a crown plate closing the top of the 110 furnace and arranged to be heated thereby, said plate being provided with corrugations upon its upper surface; a perforated pipe mounted above the crown plate for spraying a disinfecting agent upon the corrugated surface thereof whereby said agent may be vaporized; and racks mounted above the furnace to support articles to be disinfected by the vaporized agent. 115
10. A disinfecting apparatus comprising the combination with a closed compartment 120
- 125
- 130

of a furnace mounted within the compartment; a crown plate mounted upon the top of the furnace, said plate being provided with corrugations formed upon its upper 5 surface and ribs formed upon its lower surface; a perforated pipe mounted above the crown plate; means for delivering a disinfecting agent to said pipe whereby said agent may be sprayed upon the corrugated 10 surface of the crown plate and thereby vaporized; and means for supporting articles to be disinfected above the furnace whereby the vaporized agent may permeate said articles.

15 11. A disinfecting apparatus comprising
the combination with a closed compartment
of a furnace mounted within the compartment;
a crown plate mounted upon the top
of the furnace, said plate being provided
20 with corrugations formed upon its upper
surface and ribs formed upon its lower surface;
a perforated pipe mounted above the
crown plate; means for delivering a disin-
fecting agent to said pipe whereby said
25 agent may be sprayed upon the corrugated
surface of the crown plate and thereby va-
porized; a zigzag chimney connected to the
furnace; and racks mounted above the fur-
nace and the chimney for supporting articles
30 to be disinfected.

12. A disinfecting apparatus comprising the combination with a closed compartment of a furnace mounted within the compartment; a crown plate mounted upon the top of the furnace, said plate being provided with corrugations formed upon its upper surface and ribs formed upon its lower surface; a perforated pipe mounted above the crown plate; means for delivering a disinfecting agent to said pipe whereby said agent may be sprayed upon the corrugated surface of the crown plate and thereby va-

porized; a zigzag chimney connected to the furnace; and racks mounted above the furnace and the chimney for supporting articles to be disinfected; and shields mounted between the furnace and chimney and the racks to protect the articles from burning.

13. A disinfecting apparatus comprising the combination with a closed compartment of a furnace mounted within the compartment; a crown plate mounted upon the top of the furnace, said plate being provided with corrugations formed upon its upper surface and ribs formed upon its lower surface; a perforated pipe mounted above the crown plate; means for delivering a disinfecting agent to said pipe whereby said agent may be sprayed upon the corrugated surface of the crown plate and thereby vaporized; a zigzag chimney connected to the furnace; and racks mounted above the furnace and the chimney for supporting articles to be disinfected; and shields mounted between the furnace and chimney and the racks to protect the articles from burning, said shields having perforations formed therein to permit the circulation of air and vapor upwardly therethrough to permeate the articles to be disinfected.

14. In a disinfecting apparatus, the combination with a furnace adapted to be installed within a closed compartment, of a crown plate mounted upon the top of the furnace and provided with corrugations formed upon its upper surface and ribs formed upon its under surface; and spraying means mounted directly above the plate and arranged to dispense a disinfecting agent upon the plate to vaporize said agent.

In witness whereof we hereunto set our signatures.

MICHAEL TROOTNEFF.
JOHN GROMEEKO.
